HYDRO-PNEUMATIC PUMP

Filed Jan. 6, 1934

UNITED STATES PATENT OFFICE

1,994,341

HYDROPNEUMATIC PUMP

Octave Fonson and André Arthur Emile Goffin,
Brussels, Belgium; said Goffin assignor to said
Fonson

Application January 6, 1934, Serial No. 705,584
In Belgium January 7, 1933

3 Claims. (Cl. 230—90)

This invention relates to hydro-pneumatic pumps in which a gaseous fluid, such as air, is compressed to any given pressure by means of a liquid under pressure such as water from the mains, the said liquid acting directly upon the gaseous fluid and not through mechanical means such as pistons, diaphragms, etc.

More particularly the invention is concerned with that type of pump or compressor in which a liquid under pressure is admitted at the bottom of a cylinder in which there is a float which by the downward and upward movement thereof, due to its own weight and to the action of the liquid, operates successively to admit the gaseous fluid for compression, the admission of the liquid under pressure, the exhaust of same with, in some cases, the closing of the outlet opening of the compressed gaseous fluid. When compressors of this type are automatic, which is generally desirable, they have the inconvenience of requiring, inside the body thereof, mechanical members set in action by the float. Furthermore if the functioning is entirely automatic the outlet of compressed gas is stopped during the exhaust of the liquid, which requires the provision of a receiver for the compressed gas.

For the principal applications contemplated, for instance for elevating beer or other liquids, it will be desirable to ensure a continuous supply of compressed gaseous fluid, without using compressed gas reservoirs or bottles. These apparatus being destined for use in such places as cafés, and the like, it is advisable to consider the viewpoints of available space and of safety. Also, and specially for elevating beer, it is a recognized fact that air preserved some time under pressure is harmful for beer, whereas air freshly compressed and still saturated with water improves the beer and produces a delicious and consistent froth, which lasts and prevents the product from becoming flat. There is consequently, if not absolutely necessary, at least great advantage in compressing the air only as it is immediately required, and this necessitates an apparatus having a continuous output, yet functioning automatically. These objects and others which will appear hereinafter have been embodied in the compressor according to this invention, to be particularly described and ascertained, reference being made to the accompanying drawing in which Fig. 1 and Fig. 2 are schematical vertical sections of two forms of constructions of the apparatus by way of example.

The apparatus of Fig. 1 comprises two vertical, hermetically closed, cylindrical bodies, 1 and 1',

which may be identical in dimensions, or not. Each of said bodies however is similar in construction and comprises at the top a valve 2, (2') for admission of air or of another suitable gaseous fluid, to be compressed, and a branching 3, (3') with a pipe 4 which leads to the barrel from which the liquid has to be elevated. This branching 3, (3') comprises, in the upper portion thereof, a flap valve 5, (5') which prevents backward return of the fluid to the cylinder 1, (1'), and the lower portion thereof may be closed by a valve 6, (6') carried at the upper end of a rod 7, (7') which extends along the entire height of the body 1, (1') and has fixed thereon a float 8, (8'). The rod 7 (7') may be slidably guided in bushings, but as is illustrated can be guided only by the float which has nearly the diameter of the cylinder.

The bottom end of rods 7, (7') carries a valve flap 9, (9') which normally, by the weight of the float and of the rod, closes the entrance of a pipe 10, (10') starting at the bottom of the cylinder and terminating as a horizontal cylinder 11, (11') for a piston 12, (12') displaceable therein. The two pistons 12 and 12' are connected by means of a rod 13 having a pin 14 engaged in a slot 15 of the operating lever 16 of a four-way cock 17. This cock controls simultaneously the pipe 18 from the water mains, or any liquid under pressure, the discharge pipe 19, and two pipes 20, (20') leading to the bottom of the cylinders 1, (1') respectively.

In considering the position illustrated in the drawing, the cock 17 has connected pipes 18 and 20', also pipes 19 and 20. The water under pressure from 18 flows into cylinder 1' filled with air under atmospheric pressure; the water by rising in the cylinder compresses the air which, as soon as it reaches the pressure required in pipe 4 for elevating the liquid, opens the flap 5' to flow in pipe 4. The air so compressed does not contact with any moving mechanical member such as a piston with oil or grease and is therefore not contaminated by parts of the apparatus but may be cleansed or pumped by passing it through a filter. The compressed air has only been in contact with water and with the damp walls of the cylinder, and has therefore been saturated with moisture which is most favorable for the froth, and the taste of beer when delivered. When the water reaches about the equator of the spherical float 8', the latter is raised, closing the valve 6' and opening the valve 9'. The water then exerts pressure in the cylinder 11' displacing the piston 12' which turns the lever 16 and changes the cock the other

way round, communicating pipe 20' with pipe 19 which discharges the cylinder 1' and brings the float 8' down again, and establishes communication between pipes 18 and 20, thereby allowing the water under pressure to enter cylinder 1 where in the same cycle of operations is repeated. On the other hand, the displacement of the piston 12' produces the opposite displacement of piston 12 in its respective cylinder and the changing of the cock as soon as the float 8 rises.

By the provision of the servo-motor 11-11', the two compressor cylinders 1, 1' operate alternately, producing compressed gaseous fluid practically continuously. With one single cylinder the production is forcibly interrupted while the cylinder is emptied of its water.

It will be understood that the valves 6, 6' are not absolutely necessary and that they are only provided as an additional safety in case the floats fail to descend, or if the cock fails to operate or develops a leak. The pipe 18 may comprise a safety cock. Practically, the apparatus functions automatically and without stop until the pressure in the pipe and the barrel is equal to the pressure of the liquid in pipe 18. The apparatus then ceases functioning, and will start functioning again when a quantity of beer or other liquid has been taken from the barrel, or when the pressure in the barrel falls for any reason.

It will be understood also that the cylinders 1, 1' can be fed with another gas than air, or one cylinder can be fed with air and the other with another gas, the air and the gas then being mixed in a proportion which depends of the respective volumes of the two cylinders and of the position of the floats in the two cylinders.

In this pump, to attain the maximum efficiency for a given pressure of liquid, the diameter of the valve operating the servo-motor and the float must have determined, calculated, dimensions and weight, the calculations for which are based on the maximum pressure of the liquid which is used. However the pressure of the liquid, such as water from the mains may vary considerably, so that the apparatus will rarely function with the maximum efficiency.

The modification according to Fig. 2 has for its object to obviate this inconvenience and to provide maximum efficiency for the apparatus for all pressures which can usually be contemplated. In this modification each cylindrical body is identical to those of Fig. 1, except that for the valves 9-9' are substituted cocks 21, 21' for the pipes 10, 10'. Both pipes open respectively into the two ends of a small cylinder 22 in which are displaceable two tandem pistons 23 having a rod 13 which operates the four-way cock 17 of the servo-motor. The cock 17 is branched as before on the pipe 18 from the mains, on the pipes 20-20' and on the discharge pipe 19. Each of the cocks 21, 21' is operated by a rod 24 connected to a rod 25 attached to a lower float 26. On the said rod 25 there is formed an extension carrying the pivot 27 of a bell-crank lever 28, one arm of which forms a hook 29 cooperating with a fixed projection 30 inside the cylinder, the other arm being connected to a rod 31 carried by the upper float 32. In the lower position of the float 26, the cock 21 is closed (left hand side of Fig. 2) and the float 26 cannot rise because the hook 29 is caught under the projection 30. The liquid by rising inside the cylinder will finally raise the float 32 (as on the right hand side of Fig. 2) which produces pivoting of the hook 29 and disengages same from the projection 30, thereby allowing float 26 to rise and

open the cock 21, by turning same a quarter of a complete revolution.

It will be observed that in this modification the valves 6, 6' have been dispensed with; the servo-motor operates in the same manner as in the first modification, the pressure of the small quantity of gaseous fluid left at the top of the cylindrical body when the cock 21 is opened, being used to operate full displacement of piston 23 and the change over with practically no interruption of the feed.

What we claim and desire to secure by Letters Patent is:

1. Hydro-pneumatic pump for automatically compressing a gaseous fluid, by means of liquid under pressure, when the pressure in said reservoir falls below the pressure of said liquid, comprising in combination two cylindrical bodies, a one way inlet valve in the top portion of said bodies for admitting gaseous fluid in same, a connection between the top portion of each of said bodies and the said reservoirs separately providing a valve preventing return of the fluid in each of said bodies, pipes separately connecting the bottom of each cylindrical body to a four-way cock, a conduit leading from the bottom of each cylindrical body to a separate cylinder, a piston in each of said cylinders connected to the lever of said four-way cock, a valve operatively connected to a float in each cylindrical body and normally closing said conduit, the upward movement of the float, when a cylindrical body is full, opening said last mentioned valve and admitting pressure of the liquid on the respective piston, said piston thereby changing over the four-way cock to communicate the bottom portion of the respective cylindrical body with an exhaust pipe, and the other cylindrical body with the source of liquid under pressure.

2. Hydro-pneumatic pump for automatically compressing a gaseous fluid, by means of liquid under pressure, when the pressure in said reservoir falls below the pressure of said liquid, comprising in combination two cylindrical bodies, a float in each of said bodies, a one way inlet valve in the top portion of said bodies for admitting gaseous fluid in same, a connection between the top portion of each of said bodies and the said reservoirs separately providing a valve preventing return of the fluid in each of said bodies, pipes separately connecting the bottom of each cylindrical body to a four-way cock, alternately connecting each cylindrical body with the source of liquid under pressure, and alternately the other cylindrical body with an exhaust, two oppositely disposed cylinders connected respectively to the bottom of the two cylindrical bodies, two oppositely disposed pistons in said cylinders connected by a common rod to the operating lever of the four-way cock, the float in each cylindrical body being integral with a vertical rod carrying at the lower end thereof a valve normally closing communication between the respective cylindrical body and cylinder and the top end thereof a second valve, the float being disposed at such a height on said rod that when the respective cylindrical body is full of liquid the upward movement of the float causes said second valve to close communication with the said reservoirs, whilst said first valve to open, whereby pressure of the liquid on the respective piston will operate change over of the four-way cock.

3. Hydro-pneumatic pump for automatically compressing a gaseous fluid, by means of liquid under pressure, when the pressure in said reservoir

voir falls below the pressure of said liquid, comprising in combination two cylindrical bodies, a one way inlet valve for admitting gaseous fluid in same, a connection between the top portion of each of said bodies and the said reservoirs separately providing a valve preventing return of the fluid in each of said bodies, pipes separately connecting the bottom of each cylindrical body to a four-way cock, alternately connecting each cylindrical body with the source of liquid under pressure, and alternately the other cylindrical body with an exhaust, two oppositely disposed cylinders connected respectively to the bottom of the two cylindrical bodies, two oppositely disposed pistons 10 in said cylinders connected by a common rod to the operating lever of the four-way cock, a float

in the bottom portion of each of said cylindrical bodies operatively connected to a valve allowing connection with the respective cylinder, means holding said float in a lower position whereby said last mentioned valve is closed, and a second float 5 connected to said means and situated in the upper portion of said cylindrical body, whereby the liquid under pressure reaching the top of each cylindrical body will lift said second float thereby disconnecting the first float from its holding means, whereby said second float opens the last mentioned valve for admitting the liquid under pressure upon the respective piston that operates change over of the four-way cock.
